August A. Quedensley,
By Charles J. Schmidt, Atty.

UNITED STATES PATENT OFFICE.

CHARLES F. SCHROEDER AND AUGUST A. QUEDENSLEY, OF CHICAGO, ILLINOIS.

HAMMER.

Application filed January 19, 1922. Serial No. 530,471.

To all whom it may concern:

Be it known that we, CHARLES F. SCHROEDER and AUGUST A. QUEDENSLEY, both citizens of the United States, and residents of Chicago, in the county of Cook and State of Illinois, have invented certain new and useful Improvements in Hammers, of which the following is a specification.

Our invention relates to hammers and particularly to improved means for securely and interchangeably supporting on the hammer body, tips or facing of softer metal or other material to enable the hammer to be used for striking work without marring it.

15 One important feature of the invention is to provide means whereby the desired tips or faces can be quickly and readily applied or removed. Another important feature is to provide such construction for securing the tips rigidly in place that blows on the tip will be directly transmitted to the hammer body and not to screws, bolts or other members which secure the tip-holding parts together, such direct transmission of blows 25 preventing loosening and subsequent rattling or vibrating of the hammer parts.

The above and other features of our invention are incorporated in the structure shown on the accompanying drawing, in 30 which drawing

Fig. 1 is a side elevational view of a hammer head with part of the handle,

Fig. 2 is a side elevational view of the head body section with one tip, and the tip securing plate removed,

Fig. 3 is an end elevational view of the hammer head,

Fig. 4 is an end elevational view with the clamp or plate member removed,

40 Fig. 5 is a sectional view on plane 5—5, Fig. 3,

Fig. 6 is a sectional view on plane 6—6, Fig. 3,

Fig. 7 is a sectional view similar to Fig. 45 5, showing a modified arrangement, and

Fig. 8 is a sectional view on plane 8—8, Fig. 7.

The hammer head comprises the body part indicated as a whole by A and the cover or 50 clamping part indicated as a whole by B. The body part A comprises the inner or core section 10 and the outer section 11 which is integral therewith. As shown the core section is of frusto-conical shape decreasing in 55 diameter from the center to the ends. The

outer part 11 extends around only one-half of the core part and is in the form of a layer of metal which projects a distance beyond the ends of the core part 10 to form the semi-circular dove-tail pockets 12 and 13.

Extending transversely and diametrically through the body part A is the handle receiving passageway 14, for receiving a suitable handle H. Extending from the core part 10 at the side opposite the part 11 is the flange or boss 15 which surrounds the end of the passageway 14 and serves to receive the opening 16 in the clamping member B which is of the same shape as the part 11 and which when applied to the body part 15 A intimately will cover the other half of the core part. When the part B is applied it fits snugly against the core part 10 and its boss 15, and its ends 17 and 18 which overhang the ends of the core part will form semi-circular dove-tail pockets 19 and 20 which register with the dove-tail pockets 12 and 13 to form circular dove-tail pockets for receiving facing or tip members F. Suitable securing means such as screws 21 may be used 80 for rigidly securing the clamping member B to the body part A. To accurately guide part B into clamping position and to give it a snugger fit on the boss 15, the outer face of the boss is tapered and the opening 16 of the part B is correspondingly tapered as indicated at 22 so that when the part B is secured by the screws its surfaces will intimately engage with the outer surfaces of the core part 10 and boss 15 thus making a solid 90 and rigid structure.

The hammer faces or tips F may be of metal, rubber, fiber or any desired material and are provided with frusto-conical or dove-tail extensions 23 for receiving the 95 dove-tail pockets formed by the hammer head parts A and B. The faces can be readily interchangeably applied. The clamping part B is removed and the faces are then applied in the dove-tail pockets 12 and 13 and then when the part B is applied the pockets 19 and 20 will receive the faces and they will be securely, rigidly and solidly locked to the hammer head. All blows on the faces will be directly communicated to the body 100 part A of the hammer and the screws 21 will be entirely free from strain. The clamping part B by intimately engaging with the core part 10 and the boss 15 will transmit blows directly to the body A, so that the hammer 110

can be used with the same efficiency as though the head and faces were integral and solid.

In the modifications shown in Figs. 7 and 8, the two parts C and D of the head are alike except that the part B has the flange 24 integral therewith for receiving the opening 25 in the part D, a handle when inserted being thus engaged entirely by the part C. 10 The flange and opening 25 are also tapered so as to assure a secure and rigid fit of the parts.

Having described our invention, we claim as follows:

- 15 1. In a hammer head, the combination of a solid one-piece body part, a boss on one side of said body part, there being a passageway through said body part and boss for receiving and securing a handle, the ends 20 at one side of said body part projecting to form semi-circular dovetail pockets, a clamping part intimately fitting against the side of the body part and having a hole for receiving the body part boss, said clamping 25 part overhanging the ends of the body part to form semi-circular dovetail pockets for cooperating with the pockets of the body part, hammer faces having dovetail extensions for being received in said pockets, and 30 screws for holding said clamping part to the body part, said boss being tapered and said clamping part hole being correspondingly tapered to intimately receive said boss when 35 said clamping part is secured to the body part by said screws, whereby blows against the hammer faces will be transmitted entirely through the clamping part and boss

directly to the body part and said screws relieved from all transverse strain.

2. In a hammer head, the combination of 40 a body part and clamping part, said body part comprising a core section of circular cross section and an enveloping section half way surrounding said core section, said enveloping section extending beyond the ends 45 of the core section to form semi-circular dovetail pockets, said clamping part being of the same shape as said enveloping section, screws for detachably securing said sections together, said clamping part extending beyond the ends of the body part and forming semi-circular dovetail pockets registering with the pockets on the body part, hammer 50 faces having dovetail extensions engaging in said pockets to be clamped in place when 55 said body and clamping parts are secured together by said screws, a boss on said core section, there being a hole through said body part and boss for receiving a handle, said boss being tapered, and said clamping part 60 having a hole tapered to intimately and securely fit said boss when said clamping part is secured to the body part by said screws, whereby blows against the hammer faces will be transmitted through said clamping 65 part and boss directly to the body part and said screws protected against transverse strain.

In witness whereof, we hereunto subscribe our names this 12th day of January, A. D., 70 1922.

CHARLES F. SCHROEDER.
AUGUST A. QUEDENSLEY.
